UNITED STATES PATENT OFFICE.

LINN BOYD BENTON, OF MILWAUKEE, WISCONSIN.

DESIGN FOR TYPE.

SPECIFICATION forming part of Design No. 18,775, dated December 4, 1888.

Application filed May 31, 1884. Serial No. 133,406. Term of patent 7 years.

To all whom it may concern:

Be it known that I, LINN BOYD BENTON, of Milwaukee, in the county of Milwaukee and State of Wisconsin, have invented a new and original Design for Type, of which the following is a specification, reference being had to the accompanying printed impressions, forming a part thereof.

My invention relates to Italic body type, as distinguished from "Roman" and "job" type, so called.

It consists, essentially, of lower-case Italic body type formed after the analogy of lower-case Roman body type with slender light-faced stems and straight or nearly straight horizontal hair-line ceriphs.

I do not claim the design for a font of lower-case Italic type having bold-faced stems with straight hair-line ceriphs or a font of bold-faced Italic with heavy straight ceriphs, the distinguishing characteristics of my design

being the inclination of the characters to the right and giving them light-faced stems and straight hair-line ceriphs of about the same relative proportions as are ordinarily given to Roman body type. The design is thus adapted to body-work in place of the ordinary Italic body type.

I claim—

The design for a font of lower-case body type in which the characters are inclined to the right and the stems are light-faced and terminate in straight hair-line ceriphs, as shown and described.

In testimony that I claim the foregoing as my own I affix my signature in presence of two witnesses.

LINN BOYD BENTON.
